[57] CLAIM

The ornamental design for a surface mounted latch bolt, as shown and described.

DESCRIPTION

FIG. 1 is a perspective view of a surface-mounted latch bolt showing my new design;
FIG. 2 is an enlarged top plan view thereof;
FIG. 3 is an enlarged side elevational view thereof, the opposite side being a mirror image of that shown;
FIG. 4 is an enlarged front end elevational view thereof; and
FIG. 5 is a perspective view thereof, with the bolt shown in an extended position.

FIG. 1

FIG. 2

FIG. 3

FIG. 4

FIG. 5
